UNITED STATES PATENT OFFICE.

COUNT ROLAND BOWMAN, OF BROOKLYN, NEW YORK, ASSIGNOR OF ONE-HALF TO
FRANK CAMMARATA, OF NEW YORK, N. Y.

PEN AND PENCIL HOLDER.

Application filed October 24, 1928. Serial No. 314,649.

This invention relates to a pen and pencil holder to be interposed between the overlapping portions of the front opening of a man's negligee shirt and supported on one 5 of the buttons for closing the front of the shirt.

It is common practice among men who use fountain pens and pencils having pocket clips, and who perform their duties without 10 wearing their suit coats, to engage the clips over the ends of the front portions of their outer shirts, while the body portions of the pens or pencils project inwardly and downwardly at an inclination between the 15 overlapping front sections of the shirt's opening. The material of the shirt at this point is relatively thin and as a consequence affords but little purchase for the clip arrangement which very often fails to hold 20 the pen or pencil in the desired position.

With the foregoing in mind it is the purpose of my invention to provide a separable pocket or container, which is especially adapted to hold pens and pencils by their 25 clips, and which is conceived to be inserted between the walls of the front opening of a man's outer shirt and supported in a downwardly inclined position upon one of the buttons used to close the front opening of 30 the shirt.

A further object of the invention is to provide an article of manufacture which is simple and cheap to produce and which is highly efficient and easily applied.

35 I accomplish these objects by means of the arrangement hereinafter described, set forth in the claims and illustratively exemplified in the accompanying drawing, in which Figure 1 is a perspective view of my invention proved device operatively applied to the front opening of a men's outer shirt; Figure 2 is a front elevational view of my pencil and pen holder; Figure 3 is a substantially longitudinal sectional view taken on lines 3—3 of Figure 2, and Figure 4 is a front elevational view of a slightly modified form of the invention.

Referring to the drawings, 10 denotes the pencil and pen holder and pocket as a 50 whole, the holder comprising a front and back fabric wall 11 and 12, respectively. The holder or pocket 10 is intended to be supported on the shirt in a downwardly inclined position, as illustrated in Figure 1, so 55 that the shorter ends of the walls 11 and

12 are cut at an angle to the body portion and when the pocket is in use the ends assume an upright position parallel with the front edges of the shirt opening. The walls 11 and 12 are attached together along two 60 longer sides and lower end by a tape 13 and stitching 14, thus forming a pocket.

The rear wall 12 of the pocket at its open end is provided with a projection 15, formed of two superposed pieces of leather, leatherette or the like having their sides parallel with the corresponding sides of the walls 11 and 12. A row of stitching 16 is run completely around the projection 15, the two portions of which are disposed about the end 70 of the rear wall 12, as illustrated in Figure 3, so that the stitching at this point attaches the projection permanently to the rear wall. The front wall 11 also carries a projection 17 at its open end, the projection 75 comprising a strip of the same material as the other projection and cut in an inverted V-shape. One portion of the V projects in the general direction of the front wall 11, forming a continuation thereof, and projecting to a point short of the bottom line of the wall 11 to provide a shoulder 11^a, the same being stitched along one end to the wall 11 by stitching 18 and along its upper and lower sides to the adjacent sides of the 80 other projection 15 by continuations of the 85 tape 13 and stitching 14.

The other arm of the V-shaped piece 17 folds over on the first arm and is provided with a projection 19 which folds under the 90 second arm and is secured thereto by stitching 20 disposed marginally thereover, the upright row 21 of the stitching being disposed through the two overlying layers of the V-shaped piece adjacent the line of the 95 fold thereof. According to this construction the second portion of the piece 17 becomes a flap which engages over the edge of one side of the front opening of the shirt, as illustrated in Figures 1 and 3. In order to 100 support the pocket in usable position the upper end of the flap is provided with an extension 22 in which a button hole 23 is cut, the purpose being to receive a button 24 of one side of the front opening of the shirt. 105 The holder is further supported by the shoulder 11^a resting against the next lower button on the shirt front.

To apply the pen holder or pocket 10 is very simple, since it only requires the lower 110

inclined end of the fabric pocket to be inserted between the ends of the shirt opening, the flap or projection 19 being folded over the edge of the shirt and button hole 23 engaging over the button 24 immediately above the pocket itself. The double thickness of the folded open end of the pocket affords ample purchase for the clips of the pens and pencils placed in the container for support and if the writing instrument is not provided with a clip, the inclination of the pocket will enable it to be safely held without fear of dropping out even when the body of the user is leaning forward.

15 In Figure 4, I have shown the part 17^a cut to provide a button hole 23^a cut in a portion projecting below the holder and adapted to engage over one button of the shirt, while the upper end of the same part 20 is projected beyond the upper edge of the holder and is cut to form a hook 24 on its front edge to engage the button immediately above.

Having now described my invention, what I claim and desire to secure by Letters Patent is:

1. A pen and pencil holder of the character described, comprising a pocket portion having its open end disposed at an angle to the longitudinal axis of the pocket, and a projection for the front wall of the pocket folded over upon itself to embrace the edge

of a garment, said projection being further provided with a button hole to engage over a button on the edge of said garment. 35

2. A pen and pencil holder of the character described, comprising a pocket portion formed of superimposed layers of material attached together along all but one of the shorter ends, each end thereof being cut at, 40 an angle to the longitudinal axis of the pocket, an extension for the open end of the back layer, and an extension for the open end of the front layer comprising a piece of material attached at one end to the end 45 of the layer and folded over on itself at the other end to engage over the edge of a garment, the upper end of the second extension having an opening to engage a button on the garment. 50

3. A pen and pencil holder, as claimed in claim 2, including a tape disposed about the closed ends of the layers of material, and a row of stitching disposed through the tape and layers, substantially as described. 55

4. A pen and pencil holder, as claimed in claim 1, in which the pocket portion projects below the projection to provide a shoulder adapted to engage against the next button on the shirt. 60

In testimony whereof he has affixed his signature.

COUNT ROLAND BOWMAN.
